UNITED STATES PATENT OFFICE.

AUGUSTUS J. LEAVITT, OF NORTH EASTON, MASSACHUSETTS.

CAN-OPENER.

SPECIFICATION forming part of Letters Patent No. 269,216, dated December 19, 1882.
Application filed August 17, 1882. (No model.)

To all whom it may concern:

Be it known that I, AUGUSTUS J. LEAVITT, a citizen of the United States, residing at North Easton, in the county of Bristol and State of Massachusetts, have invented a new and useful Improvement in Can-Openers, of which the following is a full, clear, and exact description, reference being had to the accompanying drawings, in which like letters denote corresponding parts.

My invention relates to an instrument or knife to be used for opening fruit-cans and similar articles.

Figure 1 represents the knife in the operation of cutting out the top of a can. Fig. 2 is a general representation of the knife-handle and knife-blade with its several parts. Fig. 3 is a section of the prong, in which the bevel is more especially shown. Fig. 4 is a cross-section of the blade-prong at xx , showing more especially the twist of the lip b .

In utensils of this description heretofore made the knife has been formed in such a manner that the fulcrum was supplied by the top of the can, usually in the line of the cut. Sometimes they have been formed like shears; but in my invention I form the knife-blade with a prong, said prong being beveled upon one side only; and upon the opposite edge of the blade, near the handle, I form a lip, which is twisted outwardly or from the bevel side of the blade, making a slight depression near the angle formed by the twist of the lip, by which means I obtain a fulcrum upon the outside line of the cut.

In Fig. 1, C is the can. D is the top.

In Fig. 2, A represents the blade; B, the handle; a , the prong of the blade; a' , the bevel of the prong; b , the lip and the fulcrum-point d . c is a ferrule, which is preferably placed on the handle to prevent it splitting. The bevel of the prong is more particularly shown in Fig. 3.

The knife is made of steel or a similar substance, having a shank which may be of the

ordinary kind, and which is inserted in the handle B. The object of having the bevel a' formed upon one side only of the prong is that it will tend to keep the knife in a proper position for cutting out the top, and will also keep the line of cut near the edge of the top of the can. I do not intend to confine myself to this form of bevel, as the prong will work if beveled upon either edge, or, like an ordinary knife, upon both edges, though not so efficiently.

It will be observed by reference to Fig. 1 that the lip b , which is turned under or outward, projects outside the edge of the can, while the point d forms the fulcrum-point upon which the knife is moved while performing the cutting function.

The mode of operation of this utensil is exceedingly simple. The point of the prong a is inserted near the edge of the top of a can and pressed down until the point b rests upon the edge of the can. Then by pressing the handle downward the cutting-edge, beveled, as shown in Fig. 3, a' , will rapidly cut the tin or similar substance of which the can is composed, and by moving the knife along a clean cut is made at a uniform distance from the edge of the can.

Having now described my invention, what I claim, and desire to secure by Letters Patent of the United States, is—

In a can-opener, the blade A, having the prong a , sharpened upon its outer edge, and the lip b , formed upon the opposite edge of the blade from the sharpened edge of the prong, a' , said lip being turned or twisted from the side upon which the bevel is made, and provided with the depression or fulcrum-point d , all arranged and combined substantially as and for the purposes described.

AUGS. J. LEAVITT.
